UNITED STATES PATENT OFFICE.

WILLIAM W. SABIN, OF PORTLAND, OREGON, ASSIGNOR TO NORRIS B. GREGG AND J. C. HARRALSON, OF PORTLAND, OREGON.

LOCKING DEVICE FOR MOTOR-VEHICLES.

14,628.

Specification of Reissued Letters Patent. Reissued Apr. 1, 1919.

Original No. 1,715,871, dated February 13, 1917, Serial No. 126,357, filed October 18, 1918. Application for reissue filed February 10, 1919. Serial No. 276,185.

To all whom it may concern:

Be it known that I, WILLIAM W. SABIN, a citizen of the United States, residing in Portland, in the county of Multnomah and State of Oregon, have invented certain new and useful Improvements in Locking Devices for Motor-Vehicles, of which the following is a specification.

My invention relates to improvements in locking devices for motor vehicles in which the clutch lever of the motor vehicle is locked in such a position that the clutch cannot be put into its working position.

The objects of my invention are:

1st. To provide simple and inexpensive means for preventing the unauthorized operation of a motor vehicle; and

2nd. To provide a device that positively cannot be locked or unlocked except with the proper key, and that cannot readily be broken or become deranged.

I attain these objects by the design and arrangement of the several parts of the device, and by the position of the device with relation to the part of the motor vehicle mechanism, to be locked, as shown in the accompanying drawing, in which is shown an isometric view of the device in position and locked; portions of the side frame, clutch arm, clutch shaft, and floor of a motor vehicle being necessarily shown.

The device, in the specific form shown, consists of the frame 1, upward projecting casing member 1^a and the other upward projecting guard member 1^b, the bolt 2, means for imparting to bolt 2 a rectilinear motion within the slotted holes hereinafter described in 1^a and 1^b, and a lock for said means. The frame shown consists of the base 1 for securing the device to the frame of the motor vehicle, a bottom member projecting outwardly from said base, a rib supporting said outwardly projecting member and the members 1^a and 1^b projecting upwardly from the top of the outwardly projecting member. 1, 1^a and 1^b may be made of several pieces joined in an approved manner, but I prefer to make it in one piece, and a casting. The frame is riveted to the side frame 8 of the motor vehicle at the proper place and position to encompass the clutch arm 6 of the motor vehicle within the space between the bolt 2, the upwardly projecting members 1^a and 1^b, and

that part of the outwardly projecting member of frame 1 directly under the bolt. In 55 1^a and 1^b are oppositely arranged transverse holes forming guides for the bolt 2. The diameter or transverse width of 1^a is such that the bolt 2 is guided by the slot in 1^a with sufficient precision to permit it to readily enter the slot in 1^b. To further insure smooth action the end edges of the bolt and the edges of the slots on the inner face of 1^b are slightly chamfered. In order to provide for the slight variation in the position 65 of the clutch arm due to different makes of motor vehicle, several slots are provided, thus giving an adjustability in a vertical direction. Transverse adjustability is readily provided for in the frame 1 by varying the 70 distance of its attaching face from the upwardly projecting members 1^a and 1^b. This is readily accomplished in the pattern, if a casting is used. The upwardly projecting member 1^a is of a length to just project 75 through the floor board 9 of the motor vehicle, the casting being long enough to suit the largest type of motor vehicle and cut to length required for any particular motor vehicle. In the center of 1^a is an axial hole in 80 which is located the means of imparting the desired rectilinear motion to the bolt 2 as hereinafter described.

The bolt 2 may be of any desired section and material but I prefer to make it of steel, 85 and as shown, with a triangular cross section, and with the apex of the triangle flattened and the bolt located with the flattened apex on the under side. The length of bolt 2 is such that its ends when in its locked 90 position, are flush with the outside faces of 1^a and 1^b and when in its unlocked position, its inner end is flush with the inside of 1^a.

In the bolt 2 is a centrally located longitudinal opening through the bolt in a direction transverse to the axis of the upwardly projecting member 1^a. One of the longitudinal sides of this opening has on it teeth of a proper size and pitch to mesh with the teeth of the pinion hereinafter described. 100 The opening in the bolt is of a width just sufficient to allow clearance for the pinion, and consequently prevents the pinion from getting out of gear. The amount of rectilinear movement of the bolt is determined 105 by the length of the longitudinal opening,

the pinion acting as a positive stop in either direction.

For imparting to the bolt 2 the necessary rectilinear motion, a pinion 4, formed on or attached to the lower end of the extension stem of the lock hereinafter described, is provided, the teeth of the pinion meshing with the teeth on the bolt. The length of the pinion is made sufficient to accommodate the bolt in any of its vertical positions. To prevent any lateral motion of the pinion, the bottom end is made cylindrical and fits pivotally into the bottom of the axial hole.

The lock 3 is of the best type of the ordinary cylinder lock, and is attached to the upper end of 1^a by brazing or other means adequate to prevent its removal.

The device is readily assembled by determining the transverse location of the clutch arm of the motor vehicle to which the device is to be fitted, selecting the frame which will give the proper transverse dimension, inserting the bolt in the proper vertical location, cutting off the member 1^a to suit the floor height, inserting pinion and lock, and then attaching the lock, permanently. The assembled device is then riveted to the frame of the motor vehicle at the proper position as hereinbefore described.

To lock the device, the clutch arm is pressed downward until it touches the horizontal bottom member of the frame 1, throwing out the clutch, the key is inserted in the lock, and the bolt moved into the locked position as shown in the drawing. The clutch arm is then released and allowed to rest against the bolt. The upward strain of the clutch lever against bolt 2, or its impact on the bolt, if permitted to spring up suddenly, is distributed between the parallel members 1^a and 1^b, minimizing breaking strain on the bolt and twisting effect on the casing 1^a, and enabling the guide holes to be made with ample clearances without ill effect. The bolt when extended has both ends guarded by the uprights so that it is shielded against both axial and cross-wise hammer-blows so that liability to malicious breakage is greatly reduced. To unlock the device, the clutch arm is first pressed down, relieving the tension on the bolt, the key inserted, the bolt moved over to the unlocked position, and the clutch arm is then free to be operated as usual in the running of the motor vehicle. It will be seen, that since the clutch, when the device is locked, is thrown out and held thus, that, while the engine may be run, the motor vehicle absolutely cannot be moved by its propelling machinery.

This invention has the following advantages: It is extremely simple; inexpensive; easy to fit to and attach to any make of motor vehicle; can be locked or unlocked instantly and with ease; is of great strength

and durability; is difficult to break or tamper with; and positively prevents, when locked, the running of the motor vehicle without the floor being torn up and the bolt severed.

Changes in the form, proportion, and minor details of construction may be resorted to without departing from the spirit or sacrificing any of the advantages of this invention.

What I claim is:

1. In a locking device for a motor vehicle, a base member adapted to be attached to the frame thereof, said member having an outwardly projecting member, two upwardly projecting members projecting upward from the top of the outwardly projecting member; in said upwardly projecting members three pairs of oppositely arranged transverse holes; a bolt adapted to slide within and through said transverse holes; a lock attached to the upper end of one of the said upwardly projecting members; an extension stem connected to said lock, on said stem, teeth for imparting transverse rectilinear motion to said bolt, said stem being disposed within said upwardly projecting member; said complete device being disposed in such a position as to encompass and hold when in its locking position in the space between the bolt, the outwardly projecting member, and the upwardly projecting members, the clutch lever of the motor vehicle in its non-working position.

2. In a locking device for a motor vehicle, a base member adapted to be attached to the frame thereof, said member having an outwardly projecting member carrying two upwardly projecting members projecting upwardly from the top of the outwardly projecting member; in said upwardly projecting members three pairs of oppositely arranged transverse holes; a bolt adapted to slide within and through the transverse holes, said bolt having a centrally located longitudinal opening having gear teeth on one side; one of said upwardly projecting members having an axial hole; a lock attached to the upper end of said member, a pinion disposed in said axial hole; said pinion adapted to mesh with the gear teeth on the bolt and impart to said bolt transverse rectilinear motion, and an extension stem connecting said lock and pinion, said complete device disposed in such a position as to encompass and hold when in its locked position in the space between the bolt, the outwardly projecting member and the upwardly projecting members, the clutch lever of the motor vehicle in its non-working position.

3. In a locking device for a motor vehicle, a lock casing adapted to be applied in generally upright position to extend from above

to below the vehicle floor, a lock carried by the upper end of said casing, a bolt arranged to work transversely through said casing and operatively connected with the lock; 5 a guard spaced from, and substantially parallel to and with its bottom connected with, said casing, said guard being apertured to receive said bolt when the latter is projected to locking position, whereby said casing, 10 guard and bolt may freely surround a space for the reception of a lever of the automobile; and means for supporting said casing and guard.

4. In a locking device for a motor vehicle, 15 a supporting base for connection with a fixed part of the vehicle, two upwardly projecting members carried by said base and having therein laterally alining openings, a bolt slidably mounted in the opening of one said member for projection to engage in the alining opening of the other said member, said bolt having teeth thereon, a lock attached to the upper end of the bolt-carrying member and a pinion, operatively connected 20 with said lock and with the teeth of said bolt.

5. In a locking device for a motor vehicle, 25 a generally-upright casing member, adapted

to extend from above the floor of the vehicle to a point below the floor approximately to 30 the position of the vehicle clutch-lever, said casing having a transverse opening through its side walls, a lock carried by the upper portion of said casing, a pinion within said casing operatively connected with the lock and 35 extending into proximity to the transverse opening, a bolt slideable in said transverse opening and arranged in engagement with the pinion to be projected and retracted by 40 operation of the lock, a guard element substantially paralleling the casing, at its upper end spaced therefrom and at its lower end connected thereto and between its ends provided with an opening alining with the transverse opening of the casing to receive 45 the end of the bolt when the bolt is projected said casing, guard and projected bolt completely inclosing a space disposed to receive the clutch lever in its clutch-disabling position, and means rigidly to connect said 50 casing and guard to the vehicle; whereby said guard braces the projected bolt against upward displacement and shields the end of the bolt against easy fracture.

WILLIAM W. SABIN.
